ROLLER WINDOW SCREEN

Filed Sept. 14, 1928

FIG. 1

FIG. 2

FIG. 3

FIG. 4

By Clarence Walker

His Attorney

William W. Watson

UNITED STATES PATENT OFFICE

WILLIAM W. WATSON, OF JAMESTOWN, NEW YORK

ROLLER WINDOW SCREEN

Application filed September 14, 1928. Serial No. 306,051.

This invention relates to roller window screens and more particularly to improvements in the details of construction thereof.

In its preferred embodiment, this invention 5 contemplates the provision of a metal roller window screen, the construction of which provides for greater efficiency, adaptability and controlled operation. A further contemplation of this invention, is the provision 10 of improved structural details by reason of which the device is made practically impervious to the usual wear and disorder encountered in operating screens of this type.

Heretofore, in the manufacture of roller 15 window screens, insufficient attention has been centered upon details which go to make up a device of this kind. As a result of this, the screens now on the market do not meet the requirements exacted of them and 20 constant replacement thereof is necessary.

Applicant discloses, in the following specification, a roller window screen structure in which is provided a spring actuated roller mounted upon ball bearings which thus insure 25 free and even action of the screen when moved from one position to another. A suitable latch and locking device formed in the metal guide channels and the operating bar, controls the spring actuated roller as well as 30 preventing raising of the screen from the outside either by design or inadvertence.

The principal object of this invention is the provision of a roller window screen contained within a case supported in the head of 35 the window frame and which is adapted to be readily withdrawn therefrom to completely screen a given window.

Another object of this invention is the provision of a screen supporting roller having 40 means by which to adjust the tension of the spring which acts to retract the screen.

A further object of this invention is the provision of a screen supporting roller mounted upon ball bearings which assure a free and 45 even action of the screen.

A still further object of this invention is the provision of an operating bar having an automatic latch for ordinary operation 50 and a positive lock which, when the screen is

fully extended, prevents undesired lifting of the screen from the exterior of the window.

Other and further objects of this invention will appear from a consideration of the following specification taken in connection 55 with the accompanying drawing, and in which

Fig. 1 is a front elevation of a window frame having secured thereto and in partially extended position one modification of the 60 present invention;

Fig. 2 is an enlarged sectional view and discloses the details of construction of the screen roller and actuating spring;

Fig. 3 is a view similar to that of Fig. 2 65 showing the actuating spring in the position it assumes when the screen is fully extended;

Fig. 4 is an end view of the structure shown in Fig. 3 being taken on the line 4—4 of that figure and shows the device by which initial 70 or any varying degree of tension of the actuating spring is obtained.

Referring to the drawing, the reference numeral 10 is employed to designate a window frame in which is mounted, within or adjacent the head jamb 11, a roll case 12. Secured to the vertical jambs of the frame 10 in accordance with any one of the showings of the drawing, are metal or wood guide channels 13 and 14. Extending from the roll case 12, as shown in Fig. 1, is a wire mesh screen 15, having secured at the lower edge thereof an operating bar 16, through the use of which the screen may be moved to or from the roll case 12 as desired.

The roll case 12, as shown in Figs. 2, 3, and 4 of the drawing, is formed from a rectangularly shaped strip, the longitudinal edges of which are properly spaced to provide passage for the screen 15 therethrough. The ends of the roll case are provided with projecting tongues 18 which are adapted to engage end plates 19 through suitable openings and are headed over to secure the end plates to the case whereby to create a rigid and substantial box-like structure. The end plates 19, which are flanged on three sides to enclose the ends of the case 12, have formed integral therewith and upon the fourth side a downwardly extending tongue 21 having 100

suitable openings therethrough and it is by means of these tongues and the screws 23 that the roll case 12 is secured to the vertical jambs of the frame. The lower horizontal 5 wall 25 of the case 12 terminates in a roll edge 26 spaced a slight distance from the vertical wall 27 of the case.

In order to support the axle 30, which carries the screen rewinding mechanism, the 10 end plates 19 are provided with centrally located indented portions 32 (Fig. 4). Two offset ribs 33 are formed in the circumferential walls of the portion 32 being diametrically opposite each other and for a purpose 15 about to be described. A centrally located flanged opening 34 is provided in the depressed portion 32 and is of a diameter sufficient to permit the free entrance of the end of the axle 30. The ends of the axle 30 are provided with slots 35 adapted to be engaged by 20 tongues formed upon lock washers 36. Each lock washer 36 is provided with two diametrically opposite engaging surfaces 37 which, when it is in position upon the axle 30, permits rotation of said axle in but one direction. When the axle 30 is rotated in a 25 counter clock-wise direction, by means of a tool adapted to fit the slot 35, the contacting surfaces 37 of the lock washer 36 ride outwardly upon the raised rib surfaces 33 of the indented portion 32. However, when it is attempted to rotate the axle in a clock-wise 30 direction the surfaces 37 of the washers instantly engage the ribs 33 thereby preventing any movement in this direction.

Adjacent the indented portions 32 of the plates 19 and mounted upon each end of the axle 30 are ball bearings 40. Supported by the bearings 40 is a cylindrical roller 41, the 40 bearings 40 being pressed upon the axle 30 and the roller 41 also being pressed into engagement with said bearing. Between the end plates 19 and the ends of the roller 41 are thrust washers 42, the purpose of which 45 is to prevent the roller from coming into contact with the plates 19. These washers have an opening therethrough by which to mount them upon the indented portions 32. It is obvious that as the roller rotates in one direction or the other to permit the extension or retraction of the screen, a certain amount of end play will occur and without the aid of the washers 42, the efficient operation of the roller would be greatly impaired. Loosely 50 engaging the axle 30 is a sleeve 43, the length of which being dependent upon the length of the spring 45. The spring 45 encases the sleeve 43, one end thereof extending beyond the end of the sleeve 43. The spring at one 55 end is secured to the axle 30 preferably by means of a strap 46, welded to or otherwise suitably fastened to said axle, which strap is provided with a loop 47 to which the end-most coil of the spring is fastened. The other 60 end of the spring 45 is engaged with the 65

roller 41 through a depressed portion having an opening 48 therethrough. Attention is called to the fact that since the axle 30 is prevented from movement in a clock-wise direction, any rotation of the roller in this direction will tend to tighten the coils of the spring 45. As the screen 15, which is secured in any suitable manner as by welding to the roller 41, is unrolled from off the roller, the spring 45 will be tightened and reduced in diameter, the sleeve 43 preventing reduction beyond the elastic limit of said spring.

While only one modification of the roll case and several applications to window frame structures have been shown and described in conjunction with applicant's invention, it is obvious that other modifications or adaptations may be made without departing from the spirit and scope of the invention as set forth in the following claims.

Having thus set forth my invention, what I claim as new and for which I desire protection by Letters Patent is:

1. In a roller window screen structure, a roll case, a spring roller, spring tensioning means, said means comprising a roller axle, a lock washer secured to said axle, and means in said case engaging said washer whereby to prevent rotation of said axle in but one direction.
2. In a roller window screen structure, a roll case, an end plate in said case having an opening therethrough, a roller supporting axle in said opening, a lock washer secured to said axle adjacent said plate, and ribs in said plate cooperating with said washer whereby to prevent rotation of said axle in but one direction.
3. In a roller window screen structure, a roll case, a spring actuated roller in said case, spring tensioning means comprising ribs formed in the end plates of said case, an axle projecting through said roller and supported in said plates, lock washers secured to said axle adjacent the ends thereof, said washers being adapted, when rotated in one direction, to engage said ribs whereby to prevent rotation of said axle.
4. In a roller window screen structure, a roll case, an axle supported in the ends of said case, a roller enclosing said axle, bearings mounted on said axle, said bearings supporting said roller, ribs formed in said case ends, lock washers keyed to said axle and engageable with said ribs, and a spring encircling said axle, said spring being attached at opposite ends to said axle and said roller whereby when said axle is rotated in one direction said washers slide over said ribs causing an increase in the tension of said spring.
5. In a roller window screen structure, a roll case, a reciprocable roller in said case, unidirectional rotating means in said roller, said means comprising an axle, bearings mounted in and supporting said roller, a

sleeve on said axle, and a spring attached to said axle and said roller, ribs formed in the ends of said case and lock washers secured to said axle, said washers being adapted to engage said ribs whereby to tension said spring by preventing rotation of said axle with said roller when said roller is manually rotated.

6. In a roller screen structure, a roll case, end plates in said case, a roller supporting
10 axle mounted on said end plates, ribs in said plates, and means on said axle cooperating with said ribs to limit the rotation of said axle to one direction.

15 In testimony whereof I have affixed my
signature.

WILLIAM W. WATSON.
